COMBINED CLOSURE CAP AND DISPENSING SPOUT

Harry A. Mart, Los Angeles, Calif.

Application January 24, 1955, Serial No. 34,160

Term of patent 14 years

(Cl. D58—26)

FIG. 1

FIG. 3

Fig. 1 is a front elevational view of a combined closure cap and dispensing spout showing my new design;

Fig. 2 is a side view thereof, the view from the opposite side being the same; and

Fig. 3 is a top plan view thereof.

The essential features of my design are shown in full lines.

I claim:

The ornamental design for a combined closure cap and dispensing spout, as shown and described.
